LUBRICATING SYSTEM FOR SEWING MACHINES

Frederick F. Zeier, Fairfield, Conn., assignor to
The Singer Manufacturing Company, Elizabeth, N. J., a corporation of New Jersey

Original application April 15, 1939, Serial No. 267,958. Divided and this application June 8, 1940, Serial No. 339,438

9 Claims. (Cl. 112—256)

This invention relates to sewing machines and has to do with an improved system and mechanism for automatically lubricating various operating instrumentalities, so that the sewing machine may operate at a comparatively high speed efficiently and effectively for long runs.

A more specific object of the invention is the provision in a sewing machine of a lubricant-sump containing oil adapted to be contacted by means operable only during the operation of the sewing machine for splashing the oil into selectively located reservoirs connected by conduits to distribute oil to various bearings and operating parts within the machine-frame.

A further object of the present invention is to provide novel metering devices in the various lubricant-conducting conduits whereby the quantity of oil distributed to the points requiring lubrication can be effectively controlled.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a longitudinal vertical section through the frame of a machine embodying the invention, showing the internal mechanism.

Fig. 2 represents a vertical section taken along the line 2—2, Fig. 1.

Fig. 3 is a top plan view of the bracket-arm of the machine with the head-end in section.

Fig. 4 is a vertical section taken substantially along the line 4—4, Fig. 1, showing the oil-metering device which is adapted to govern the amount of lubricant directed to the needle-bar crank and link.

Fig. 5 is an enlarged fragmentary perspective view of the lower portion of the oil-metering stem disclosed in Fig. 4.

Fig. 6 is an enlarged horizontal section taken along the line 6—6, Fig. 4.

Fig. 7 is a rear end elevation of the machine with the balance-wheel removed.

Fig. 8 is an end elevation of the counterbalanced needle-bar crank showing clearly the eccentricity of the undercut recess formed therein.

Fig. 9 is a top plan view of the machine-bed with the bracket-arm and work-supporting plate

removed therefrom to expose the mechanism within the bed.

Fig. 10 is an enlarged vertical section taken substantially along the line 10—10, Fig. 9.

Fig. 11 is an enlarged vertical section taken substantially along the line 11—11, Fig. 9.

Fig. 12 is a top plan of the machine-bed with the work-supporting plate removed to expose the lubricant-distribution piping system.

Fig. 13 is a front side elevation of the machine-bed, partly in elevation and partly in section, to further illustrate the lubricant-distribution piping system.

Fig. 14 is an enlarged vertical section taken substantially along the line 14—14, Fig. 9.

Fig. 15 is an enlarged vertical section taken substantially along the line 15—15, Fig. 9.

Fig. 16 is an enlarged vertical section taken substantially along the line 16—16, Fig. 9.

Fig. 17 is an enlarged vertical section taken substantially along the line 17—17, Fig. 9.

This application is a division of my copending application Serial No. 267,958, filed Apr. 15, 1939.

Referring more in detail to the drawings, 25 the invention is shown as embodied in a sewing machine comprising a frame including a rectangular bed 1 from one end of which rises a standard 2 of an overhanging bracket-arm 3 terminating in a head 4. The rectangular bed 1 is composed of vertically disposed front and rear side walls 5 and 6, and end walls 7 and 8. Intermediate the end walls 7 and 8 are two dividing walls 9 and 10 which separate the bed 1 into three rectangular compartments 11, 12 and 13. Disposed in compartments 11 and 12 are the beneath-the-bed stitch-forming instrumentalities and the lower four-motion feeding mechanism, together with the connections for actuating the same. Each of these two compartments is open at the bottom to permit the precipitation of spent oil, lint and dirt from the mechanism within these compartments. Compartment 13 forms the lower portion or sump of a lubricant-chamber and is closed at the bottom by means of a removable circular sheet-metal cover-plate 14.

Secured upon the rear end-portion of the bed 1, see Fig. 1, is the standard 2 of the bracket-arm 3. The standard has integrally formed therewith a vertical internal partition 15 which extends from the rear end wall 8 of the bed 1 to a cover-plate 16 detachably secured upon the top of the bracket-arm 3, and divides the space within the standard into the oil or splash-lubrication chamber 13 and a belt com-

partment 17. The open end-face of the belt compartment 17 is adapted to be closed by means of a sheet-metal plate 18 which functions to protect the operator from contacting the driving belt housed within the belt compartment 17. In order to facilitate removal of the plate 18, it is provided with two keyhole slots 19 entered by the spacing studs 20 threaded into the partition 15, and with a finger-hole 21, whereby the plate 18 may be easily grasped.

The bracket-arm 3 at the standard end is provided with an internal partition 22 and at its head-end is provided with an internal partition 23, which partitions define a compartment housing the eccentrics and some of the connections for actuating the needle and top feeding mechanism described fully in my copending application Serial No. 267,958 of which this is a division. In addition to defining the compartment, the partitions 22 and 23 provide bearing supports for the ball bearing 24 and the plain bearing 25 in which is journaled the main or arm-shaft 26. To lend support to the end-portion of the arm-shaft 26 adjacent the standard 2, there is provided an additional ball bearing 27 and supporting means therefor which are mounted in the vertical internal partition 15 of the standard 2. Fixed upon the end of the arm-shaft 26 is the usual belt-driven balance-wheel 28.

Secured upon the other end of the arm-shaft 26 is the usual counterbalanced needle-bar actuating-crank 29 fitted with a hollow crank-pin 30 connected by a tubular link 31 to a hollow pin 32 integral with a split collar 33 clamped upon the endwise reciprocating needle-bar 34 carrying at its lower end the needle 34'. The needle-bar 34 is journaled in the two spaced lugs 35 and 36 formed upon the vibratory frame 37 pivotally hung at its upper end upon a stud 38 secured by screws 39 in the top of the head 4. The vibratory frame 37 is adapted to vibrate in the line of feed in timed relation with the various feeding elements and it derives its vibratory movement from an adjustable eccentric 40 secured upon the arm-shaft 26 within the compartment in the bracket-arm defined by the partitions 22 and 23. The mechanism used to connect the vibratory frame 37 with the adjustable eccentric is fully illustrated and described in my copending application Serial No. 267,958, above referred to, and therefore no further description need herein be required.

Cooperating with the needle 34' in advancing the work through the machine is a top feed-dog 41 carried on the lower end of a feed-bar 42 vertically reciprocable in a suitable bearing provided in the vibratory frame 37. Cooperating with the top feed-dog 41 is a presser-foot 43 carried on the lower end of a presser-bar 44 vertically slidable in the machine-head 4 and yieldingly biased into engagement with the work by a leaf-spring 45. The feed-bar 42 and presser-bar 44 are connected to be alternately raised and lowered in proper sequence through suitable connections with an eccentric 46 secured upon the arm-shaft 26 adjacent the adjustable eccentric 40. The connections utilized to alternately raise and lower the feed-dog 41 and presser-foot 43 are also fully disclosed and described in my copending application Serial No. 267,958, above referred to, and therefore no further description of these elements need herein be required.

Longitudinally of the bed 1 there is journaled in the plain bearing 47, ball bearing 48 and ball bearing 49, which are fixed in the walls 9, 10 and 8, respectively, the lower rotary main-shaft 50 connected at one end to the arm-shaft 26 to rotate at a one-to-one ratio by a conventional clip-belt 51 located in the belt compartment 17 of the standard 2. The main-shaft 50 has fixed thereto within the compartments 11 and 12 eccentrics 52, 53 and 54 for actuating the lower four-motion feeding mechanism and the loop-spreader mechanism, and a looper-actuating crank 55 for imparting loop-seizing and -shedding movements to the looper 56 which operates with the needle 34' in the formation of stitches. Inasmuch as the looper-mechanism, spreader mechanism and lower four-motion feeding mechanism illustrated in the present drawings are identical with those disclosed and fully described in my copending application Serial No. 267,958, above referred to, no further description of these mechanisms need be given.

Considering now the automatic lubricating system used to thoroughly oil all the bearing points in the machine, in the bed 1 and standard 2 is an oil-chamber 13 having a sump closed at the bottom by means of a removable circular cover-plate 14, see Fig. 1. Oil is introduced into the sump through an oil-cup 57 threaded into the wall 10 of the bed, the level of the oil being determined by the top of the oil-cup. Contacting the oil contained in the chamber 13 is an oil-sling in the form of a ring 58 running on a grooved driving collar 59 secured upon the lower main-shaft 50. This oil-sling during the operation of the machine creates an oil-mist throughout the entire oil-chamber 13 of the machine and the oil particles suspended in this atmosphere are deposited upon a downwardly inclined collector-plate 60 at the top of the chamber 13. The oil upon the collector-plate 60 runs down the same and into an open-topped reservoir 61 sustained in position at the upper end of the chamber 13 by two retaining screws 62. Projecting into the reservoir 61 is a horizontal lubricant-conduit 63 which extends lengthwise of and within the confines of the bracket-arm 3 and terminates in the partition 23 adjacent the machine-head 4.

Mounted upon the conduit 63 adjacent the partition 23 is a rectangular block 64, shown in section in Fig. 2, held against endwise movement by screws 65 which bear against the conduit 63. Drilled lengthwise of the block 64 is a bore 66 connected by an inclined duct 67 to the conduit 63. Disposed in the bore 66 are wicks 68, the free ends of which project beyond the ends of the block 64 and are positioned to be contacted by the wicks 69 and 70 disposed in cavities formed in the pitmans 71 and 72, respectively, of the top feeding mechanism, see Fig. 3, thereby to distribute oil on the faces of the eccentrics 40 and 46, and through the longitudinal bores 73 and 74 of the pitmans 71 and 72 to the pivot-points. It will be understood from the above that oil is conducted from the conduit 63 to some of the bearing points in the top feeding mechanism, and that the amount of oil delivered is effectively controlled by metering screws 75 in the block 64 which are adapted to compress and so vary the porosity of the wicks 68.

Referring now to Fig. 4, it will be seen that intersecting the outer end-portion of the conduit 63 in the partition 23 is a horizontal transverse

bore 76 opening into a vertical bore 77 extending through the bearing bushing 25 in the partition 23 and opening at its lower end into the arm-shaft bearing surface of the bushing 25. Adjacent the bottom of the vertical bore 77 in the bearing bushing 25, see Fig. 1, is a relatively small horizontal bore 78 terminating in a peripheral groove 79 formed in the reduced end-portion 80 of the bushing 25. The reduced end-portion 80 of the bushing 25 extends into an undercut recess 81 in the counterbalanced needle-bar crank 29, which recess, as shown in Fig. 8, is eccentrically located with respect to the longitudinal axis of the arm-shaft 26. Extending radially from that portion of the undercut recess 81 which is at the greatest distance from the axis of rotation of the arm-shaft 26 is a bore 82 opening into the central bore 83 of the hollow crank-pin 30, which central bore 83 is connected by radial ducts to a central bore 84 of the hollow needle-bar link 31. It will be understood that oil is conducted from the lubricant conduit 63, through the bores 76 and 77 to the shaft bearing surface in the bushing 25, and that oil is also conducted from the vertical bore 77 through the horizontal bore 78 to the peripheral groove 79, where the oil drips off into the undercut recess 81 and by centrifugal force is caused to move along the inclined side of the recess 81 to the point which is at the greatest distance from the axis of rotation of the arm-shaft 26 where it enters the radial bore 82 and is finally distributed to the bearings at the opposite ends of the needle-bar link 31.

In order to effectively control the amount of lubricant to be conveyed to the needle-bar mechanism, two metering devices 85 and 86 are used. The metering device 85, best shown in Figs. 4, 5 and 6, comprises a hollow stem having at its upper end a flange 87 maintained seated in a cavity 88 in the bracket-arm 3 by a lock-nut 89. At its lower end, the stem is provided with a head 90 having three vertical grooves 91, 92 and 93. Grooves 92 and 93 open into the bottom surface of the head 90 and permit the oil in the vertical bore 77 to drain into the shaft bearing in the bushing 25. Groove 93 is provided so that a portion of the oil contained in the vertical bore 77 may drain into the horizontal bore 78 in the bearing bushing 25. To vary the volume of oil delivered to the horizontal bore 78 it is only necessary to loosen the lock-nut 89, insert a screw-driver in the slot 94 in the top of the stem and turn the same to bring the groove 93 out of register more or less with the horizontal bore 78 in the bearing bushing 25. By thus varying the size of the opening between the head 90 of the metering device and the horizontal bore 78 more or less oil is delivered to the needle-bar mechanism. In the event it is desirable not to automatically lubricate the needle-bar mechanism, the horizontal bore 78 may be closed completely by turning the stem of the metering device until the groove 93 is entirely out of register with the horizontal bore 78. The stem of the metering device, see Fig. 5, is made hollow and is provided with several radial ducts 95 so that oil may be introduced into the shaft bearing in the bushing 25 by means of an oil-can prior to starting the machine after it has been at rest for a considerable period of time. It will be understood that the lubricant-conduit divides into two separate branches, one for the shaft bearing and the other for the needle-bar actuating mechanism, and that at the junction of these two branches is a metering device 85 which is effective to control

the volume of oil delivered to the needle-bar actuating mechanism.

The metering device 86 disclosed in Fig. 1 is preferably a screw-stud having an attenuated body 96 and an enlarged head 97 which fits snugly within the central bore 83 of the hollow crank-pin 30. It will be understood that the oil collected in the undercut recess 81 and delivered through the radial bore 82 is distributed to the hollow needle-bar link 34 through the passage between the bore 83 of the crank-pin 30 and the attenuated body 96 of the screw-stud 86. The amount of oil delivered to the needle-bar link 34 is controlled by turning the screw-stud in or out of the central bore 83 sufficiently for the head 97 to move across the outer end of the radial bore 82 in the counterbalanced crank 29. This shifting of the screw-stud effects a change in the size of the oil-passageway and thereby controls the distribution of the oil.

In the event that the undercut recess 81 in the counterbalanced needle-bar crank 29 becomes flooded with oil, the excess is thrown off by the oil-sling 29' integral with the crank 29 and returned within the bracket-arm 3 by the inclined drainage duct 98 in the lower portion of the bearing bushing 25. Any excess oil collected in the bracket-arm 3 is returned to the lubricant-chamber 13 through the drainage duct 99 in the partition 22.

Considering now the lubricating of the mechanisms within the bed 1, it will be observed in Figs. 7, 12 and 13 that in the lower portion of the lubricant-chamber 13 there is provided a sheet-metal oil-collecting plate 100 having depressed therein two troughs 101 and 102. Trough 101 is provided with an aperture which overlies a reservoir 103, and trough 102 is provided with an aperture and overlies a reservoir 104. Each of these reservoirs is preferably split at one end and wedged in the end-wall 8 of the bed 1 by a tapered screw 105. Secured to the other end of the reservoirs 103 and 104 are lubricant mains 106 and 107, of which main 107 is fitted with a regulating screw 108 for controlling the amount of oil delivered thereby. Projecting from the main 106 are oil-pipes 109, 110, 111 and 112, and projecting from the main 107 are oil-pipes 113, 114, 115, 116 and 117. Each of the oil-pipes projecting from the lubricant mains 106 and 107 is wick-filled and is adapted to distribute the oil by capillary attraction to the various wick-filled pockets and oil-holes in the connections and bearings in the mechanism within the bed.

Tracing the flow of oil from each oil-pipe, it will be seen from Figs. 12 and 15 that oil-pipe 109 delivers oil to an oil-hole in the lug 118 integral with the rear wall 6 of the bed 1 and that the oil is led through the oil-hole into a central bore 119 in the stationary pindle 120 and then into a central bore 121 in the feed-lift rock-shaft 122 of the lower four-motion feeding mechanism, thereby lubricating the supporting bearings therefor. Oil-pipe 110, see Figs. 10 and 12, delivers oil to the oil-hole 123 in the supporting lug 124 for the hollow rod 125 upon which is journaled for oscillation the loop-spreader actuating sleeve 126. Lubricant delivered to the bore of the hollow rod 125 is dispersed by small radial ducts 127 to the bearing surface between the hollow rod 125 and the sleeve 126. Oil-pipe 111, see Figs. 12 and 17, delivers oil to an oil-hole 128 in the wall 9 of the bed 1, the oil lubricating the bushing 129 through the duct 130 and ultimately finding its way through the cuts 131 along a central bore

132 in the feed-advance and -return rock-shaft 133, lubricating all the supporting bearings therefor. Oil-pipe 112, see Figs. 9, 12 and 14, conveys oil to an oil-hole 134 in the wall 9 of the bed 1, the oil-hole 134 terminating in the bearing surface of the bushing 47 in which is journaled the forward portion of the lower main-shaft 50. The surplus oil in this shaft bearing is collected at one end of the bushing 47 upon a reduced portion 135 thereof. This reduced portion 135 is received in an undercut 136 formed in the inner face of the looper-actuating crank 55 and the oil collected on the reduced portion 135 drips into the undercut 136 and is conveyed by a central bore 137 and radial ducts 138 in the crank-pin 139 to the sleeve 140 and the guide-rod 141. Surplus oil from the sleeve 140 and guide-rod 141 lubricates the hollow pin 142. The elements 55, 139, 140, 141 and 142 all form a portion of a looper actuating mechanism which is fully disclosed and described in my copending application Serial No. 267,958, filed April 15, 1939, referred to hereinbefore.

Oil-pipe 113, see Figs. 9, 11 and 12, delivers oil to a wick-filled pocket 143 in the pitman 144 which connects the feed-lift rock-shaft 122 with the eccentric 53 on the lower main-shaft 50. Oil in the wick-filled pocket 143 lubricates the eccentric 53 and the pivot-pin at the opposite end of the pitman 144. Oil-pipe 114, see Figs. 11 and 12, delivers oil to a laterally projecting wick 145 carried by a pitman 146 which connects the spreader mechanism with the eccentric 54 on the lower main-shaft 50. The wick 145 contacts the surface or face of the eccentric 54 and effectively lubricates the same. Oil-pipe 115, see Figs. 12 and 17, delivers oil through an oil-hole 147 in the end-portion of the feed-advance and -return rock-shaft 133 into the central bore 132, thereby assisting in furnishing oil to lubricate most of the bearings for the lower feeding mechanism. Oil-pipe 116, see Figs. 10 and 12, conveys oil to a wick-filled pocket 148 formed in the pitman 149 which connects the feed-advance and -return rock-shaft 133 with the adjustable eccentric 52 on the lower main-shaft 50, the oil in the pocket 148 lubricating the adjustable eccentric and being conveyed by the longitudinal bore 150 to the opposite end of the pitman 149. Oil-pipe 117, see Figs. 12 and 16, delivers oil through the oil-hole 151 to a central bore 152 in the tubular looper-supporting rod 153, the oil in the central bore 152 being conducted by radial ducts 154 to a cut-out 155 in the sleeve 156 upon which is clamped the looper-carrier 157.

From the above description, it will be understood that an automatic lubricating system has been provided which, while the machine is in operation, thoroughly and effectively oils all the bearing points without attention by the operator, except of course when the machine has been idle for a considerable period of time in which case priming holes have been provided, whereby the operator may initially oil the machine. Obviously any surplus oil which is thrown off by the operating parts within compartments 11 and 12 in the bed 1, or collected on the operating parts when they are not in operation, is collected in a box-like drip-pan 158 upon which the machine is adapted to rest. During the operation of the machine the oil-sling 58 creates in the lubricant-chamber 13 an atmosphere laden with oil particles which are deposited on the downwardly inclined collector-plate 60 and on the collector-plate 100. The oil thus deposited on the plates

60 and 100 runs into the reservoirs 61, 103 and 104, and from these reservoirs through suitable lubricant-conduits to all the bearing points requiring automatic lubrication. The various 5 metering devices in the lubricant-conduits provide means for effectively controlling the volume of oil distributed.

To facilitate retaining the oil-sling ring 58 in operative position upon its driving collar 59, the oil-collecting plate 100 is preferably formed with a horizontally disposed retaining finger 100' (Figs. 7 and 12) which overlies the oil-sling ring 58 and prevents the same from becoming dislodged from the driving collar 59 during shipment of the machine.

Having thus set forth the nature of the invention, what I claim herein is:

1. A sewing machine having a frame including a bed and an overhanging bracket-arm; a lubricant supply in said frame; a bearing bushing in said bracket-arm; an actuating shaft journaled in said bearing bushing; a reciprocatory needle-bar journaled in said bracket-arm and operated by mechanism including a crank fixed to said actuating shaft; means for conducting oil from said lubricant supply to said bearing bushing and to said needle-bar actuating mechanism including a vertical bore opening into the shaft bearing-surface of said bushing and a horizontal bore intersecting said vertical bore for conducting oil to said needle-bar actuating mechanism; and a metering device in said vertical bore operable to provide means for regulating the amount of oil distributed to the needle-bar actuating mechanism.

2. A sewing machine having a frame including a bed and an overhanging bracket-arm; a lubrication compartment in said frame; an oil-reservoir within said lubrication compartment; an oil-sling operable in said lubrication compartment to replenish the supply of oil in said reservoir; a bearing bushing in said bracket-arm; an actuating shaft journaled in said bushing; a needle-bar journaled in said bracket-arm and reciprocated by mechanism connected to said actuating shaft; a vertical bore in said bracket-arm opening into the shaft bearing-surface of said bushing; means including a conduit connecting said oil-reservoir with said vertical bore for delivering oil to said shaft bearing; a horizontal bore intersecting said vertical bore for delivering oil to the needle-bar actuating mechanism; and a metering device operable to provide means for regulating the amount of oil distributed to the needle-bar actuating mechanism.

3. A sewing machine having a frame including a bracket-arm; a bearing bushing fixed in said bracket-arm, said bearing bushing having a reduced end-portion; means for delivering oil to said end-portion; an actuating shaft journaled in said bearing bushing; a needle-bar journaled in said bracket-arm; mechanism including a crank secured to said actuating shaft for operating said needle-bar, said crank formed with an eccentrically disposed recess adapted to receive the reduced end-portion of said bearing bushing so as to collect oil therefrom; and means connected to the eccentrically disposed recess at the point of maximum distance from the actuating shaft to deliver oil collected in said recess to the needle-bar actuating mechanism.

4. A sewing machine having a frame including a bracket-arm; a bearing bushing fixed in said bracket-arm, said bearing bushing having

a reduced end-portion; an actuating shaft journaled in said bearing bushing; means including a vertical bore opening into the shaft bearing surface in said bushing and connected by a substantially horizontal bore to the reduced end-portion of said bushing for delivering oil to said shaft bearing and to said reduced end-portion; a needle-bar journaled in said bracket-arm; mechanism including a crank secured to said actuating shaft for operating said needle-bar, said crank formed with an eccentrically located recess adapted to receive the reduced end-portion of said bushing for the collection of oil therefrom; means connected to the eccentrically located recess at the point of maximum distance from the actuating shaft to deliver oil collected in said recess to the needle-bar actuating mechanism; and a metering device in said vertical bore operable to provide means for regulating the amount of oil distributed to the needle-bar actuating mechanism.

5. A sewing machine having a frame including a bracket-arm; a lubrication compartment in said frame; a shaft extending through said lubrication compartment; an oil-agitator located adjacent the bottom of lubrication compartment and actuated by the above mentioned shaft; a reservoir within said lubrication compartment adapted to be replenished by said oil-agitator during operation of the machine; a bearing bushing fixed in said bracket-arm, said bearing bushing having a reduced end-portion; an actuating shaft journaled in said bearing bushing; lubricant conducting means including a vertical bore opening into the shaft bearing surface in said bushing and connected by a substantially horizontal bore to the reduced end-portion of said bushing for delivering oil collected in said reservoir to said shaft bearing and to said reduced end-portion; a needle-bar journaled in said bracket-arm; mechanism including a crank secured to said actuating shaft for operating said needle-bar, said crank formed with an eccentrically located recess adapted to receive the reduced end-portion of said bushing for the collection of oil therefrom; means connected to the eccentrically located recess at the point of maximum distance from the actuating shaft to deliver oil collected in said recess to the needle-bar actuating mechanism; and a metering device in said vertical bore operable to provide means for regulating the amount of oil distributed to the needle-bar actuating mechanism.

6. A sewing machine having a frame including an overhanging bracket-arm; a bearing in said bracket-arm; an actuating shaft journaled in said bearing; a needle-carrying-bar journaled in

said bracket-arm and operated by mechanism connected to said actuating shaft; means including a lubricant-conduit having separate branches for distributing oil to said shaft-bearing and to the mechanism for operating said needle-carrying-bar; and means at the junction of said branches for regulating the volume of oil conducted by one of said branches.

7. A sewing machine having a frame including 10 a bracket-arm; a needle-carrying-bar journaled in said bracket-arm; an actuating shaft journaled in said bracket-arm; mechanism operated by said actuating shaft for imparting reciprocatory movements to said needle-carrying-bar, said 15 mechanism including a crank having a hollow crank-pin; means for conducting oil through said hollow crank-pin to lubricate said needle-carrying-bar reciprocating mechanism; and means located in the hollow of said crank-pin for regulating the volume of oil distributed to said mechanism.

8. A sewing machine having a frame including 20 a bracket-arm; a needle-carrying-bar journaled in said bracket-arm; an actuating shaft journaled in said bracket-arm; mechanism operated by said actuating shaft for imparting reciprocatory movements to said needle-carrying-bar, said mechanism including a crank having a hollow crank-pin; means for conducting oil through 25 said hollow crank-pin to lubricate said needle-carrying-bar reciprocating mechanism; and means located in the hollow of said crank-pin for regulating the volume of oil distributed to said mechanism, said last named means including a 30 stud having a reduced body portion intermediate its ends providing with said hollow crank-pin a lubricant passageway.

9. A sewing machine having a frame including 35 a bed and an overhanging bracket-arm; a lubricant supply in said frame; a bearing bushing in said frame; an actuating shaft journaled in said bearing bushing; mechanism connected to be operated by said actuating shaft; means for conducting oil from said lubricant supply to said 40 bearing bushing and to said mechanism operated by said actuating shaft including a bore opening into the shaft bearing-surface of said bushing and a duct intersecting said bore; and an oil metering device disposed in said bore for controlling the quantity of oil delivered through said 45 duct, said metering device including a stem having a head formed with a plurality of oil-conducting grooves of which one is provided with a closed end below the level of said duct for delivering oil 50 to said duct, and means provided for moving said groove relative to said duct to change the size of the oil delivery passageway.
